UNITED STATES PATENT OFFICE.

FRANK POMEROY ROWLAND, OF DONNELLY, IDAHO.

LOCKING MEANS FOR SECTIONAL CROSSCUT-SAWS.

1,219,161.

Specification of Letters Patent. Patented Mar. 13, 1917.

Application filed December 22, 1915. Serial No. 68,186.

To all whom it may concern:

Be it known that I, FRANK P. ROWLAND, a citizen of the United States, and a resident of Donnelly, in the county of Boise 5 and State of Idaho, have invented a new and Improved Locking Means for Sectional Crosscut-Saws, of which the following is a full, clear, and exact description.

My invention relates to means to connect 10 and lock the sections composing a sectional saw, the invention being particularly intended for use in cross-cut saws.

The purpose of the invention is to provide locking means whereby the sections 15 may be quickly locked securely together and readily unlocked to detach the sections when desired.

The invention will be particularly explained in the specific description following.

Reference is to be had to the accompanying drawings forming part of this specification in which similar reference characters indicate corresponding parts in all the 20 views.

Figure 1 is a side elevation of a portion 25 of a sectional cross-cut saw embodying my invention, the locking elements being shown in the unlocked positions.

Fig. 2 is a fragmentary side view showing 30 the locking elements in the locked positions;

Fig. 3 is a cross section on the line 3—3, Fig. 1; and

Fig. 4 is a cross section on the line 4—4, 35 Fig. 2.

In carrying out my invention in practice, in accordance with the illustrated example, the sections 10, 11 of the saw blade are formed with mating tongues and recesses.

40 The section 10 is shown with tongues 12, 13 preferably of unequal lengths and corresponding recesses 14, 15 in the adjacent section 11 accommodate the said tongues. The tongues and recesses range lengthwise of 45 the saw, the tongues being in the plane of the saw, as clearly shown in Fig. 3.

The formation of the longitudinal recesses 14, 15 in the section 11 results in longitudinal extending members 16, 17 and a 50 longer intermediate tongue 25 on the section 11, the members 16 and 17 being at the back of the saw and adjacent to the toothed edge respectively, there being corresponding recesses 18, 19 in the opposed section 10. The 55 tongue 25 is accommodated in a longitudinal recess 26 produced by and separating the

tongues 12, 13, of the section 10, said recess 26 extending into the section 10 beyond the bases of the tongues 12, 13 to accommodate the said tongue 25. The walls of the 60 several recesses and the edges of the tongues 12, 13, as well as the edges of the projecting members 16, 17, are V-shaped, the V-shaped edges of the tongues and projecting members being received in V-shaped depressions 65 in the walls of the recesses as clearly shown in Figs. 3 and 4 at 20, and indicated by dotted lines in Fig. 1. The end 21 of the projecting member 16 is oblique to the longitudinal direction of said member and the 70 opposed edge of the section 10 is correspondingly reentrant as at 22. Similarly there is a tapered or pointed terminal 23 on the projecting member 17, there being a corresponding V-shaped depression 24 in the section 75 10 to receive said pointed terminal 23. In addition to the projecting members 16, 17 at the top and bottom of the blade section 11, an intermediate tongue 25 is produced on the said section and extending, 80 preferably, beyond the members 16, 17.

It is to be understood that the particular number and disposition of the tongues and recesses in the respective blades may be varied, the arrangement shown being merely 85 one practical form of insuring an interengagement between mating members on the respective sections.

One of the tongues on one member is utilized as the locking tongue. Preferably, 90 the tongue 25 is utilized for this purpose and the mating recess in the opposed section is formed to co-act with the said tongue 25 in effecting the locking engagement of the sections, the locking engagement being 95 produced as follows: Said tongue 25 at its free end is longitudinally split as at 27 in order that the said end may be expandable. The sides of the tongue 25 may be continued parallel to the end. At the base 100 of the recess 26 the side walls 28 thereof are flared to accommodate the expanded terminal of the tongue 25. In order to expand the split end of the tongue 25, an oval expanding device 29 is fitted in the said 105 tongue and adapted to be given a partial turn therein. The said revoluble device 29 is accommodated in an opening produced by opposed concave depressions 30 in the tongue 25 in the opposed walls of the split 110 27, as best seen in Fig. 2. The combined recesses 30 form an oval or elliptic opening

and the walls of said opening are V-shaped in cross section, as best shown in Fig. 4, there being a peripheral V-shaped groove in the revoluble expanding element 29. The 5 expanding member 29 may be formed of two separate disks having the edges thereof beveled and the bevels being oppositely disposed, the two disks being united by a rivet 31 or the like. In the expanding element 10 29, transverse holes 32, or equivalent depressions are formed adapted to receive a wrench of the type presenting two pins, the pins of the wrench being inserted in the said holes 32 to give a quarter turn to the 15 revoluble element 29 to dispose its major axis transverse to the split 27, or to dispose said axis in alinement with said split. It will thus be seen that the sections may be instantly locked or unlocked by giving a 20 quarter turn to the element 29, the said element 29 not only serving to effect the expansion of the tongue members but serving as a lock when its major axis is disposed transversely to the expanded tongue 25 members.

Having thus described my invention I

claim as new and desire to secure by Letters Patent:

The combination of sections fitting end to end, one of said sections having a longitudinal recess therein, and the other section having a tongue split longitudinally at the end thereof, the tongue at the split thereof presenting opposed recesses forming an oblong hole in the tongue, and an oval expansion device fitting the said oblong recess and revoluble therein to bring the major axis of said device in line longitudinally with the split of the tongue or transverse thereto, the said expansion device being composed of separate side plates, the peripheral edge of said expansion device and the opposed wall of the oblong opening being correspondingly V-shaped.

In testimony whereof I have signed my name to this specification in the presence of two subscribing witnesses.

FRANK POMEROY ROWLAND.
